Primary Examiner — T. Chase Nelson*Assistant Examiner* — Ania Aman(74) *Attorney, Agent, or Firm* — Birch, Stewart, Kolasch & Birch, LLP(57) **CLAIM**

The ornamental design for a front fender for four-wheeled vehicle, as shown and described.

DESCRIPTION

FIG. 1 is a perspective view from the front and right side of a front fender for four-wheeled vehicle.

FIG. 2 is a perspective view from the rear and right side thereof.

FIG. 3 is a perspective view from the front and left side thereof.

FIG. 4 is a perspective view from the rear and left side thereof.

FIG. 5 is a front elevation view thereof.

FIG. 6 is a rear elevation view thereof.

FIG. 7 is a left side elevation view thereof.

FIG. 8 is a right side elevation view thereof.

FIG. 9 is a top plan view thereof.

FIG. 10 is a bottom plan view thereof; and,

FIG. 11 is a referential view showing the use thereof.

The broken lines shown in the drawings illustrate portions of the front fender that form no part of the claimed design.
